UNITED STATES PATENT OFFICE.

HERMAN JUILFS, OF WHITE OAK, OHIO.

CONCRETE-MIXING DRUM.

1,209,844.

Specification of Letters Patent. Patented Dec. 26, 1916.

Application filed October 4, 1915. Serial No. 54,019.

To all whom it may concern:

Be it known that I, HERMAN JUILFS, a citizen of the United States, residing at White Oak, in the county of Brown and State of Ohio, have invented certain new and useful Improvements in Concrete-Mixing Drums; and I do declare the following to be a full, clear, and exact description of the invention, such as will enable others skilled in the art to which it appertains to make and use the same.

This invention relates to new and useful improvements in concrete mixing drums, and the primary object of the invention is to provide an improved device of this character which is formed without any sharp angles in which the material to be mixed would clog, and yet will mix the same perfectly without the use of paddles or any other devices.

Another object of the invention is to provide a device which is simple and durable in construction, inexpensive to manufacture, and one which will be very efficient in operation.

With these objects in view, my invention consists of the novel features of construction, combination and arrangement of parts which will be hereinafter referred to and more particularly pointed out in the specification and claim.

In the accompanying drawings: Figure 1 is a side elevation of my improved concrete mixing drum; Fig. 2 is a top plan view of the same, and Figs. 3, 4, 5, and 6, are transverse sections of the drum, with the material therein, showing the four positions it will assume during its rotation, and the positioning of the material during the same.

In describing my invention, I shall refer to the drawing in which similar reference characters designate corresponding parts throughout the several views and in which the numeral 1 designates my improved mixing drum as an entirety, the same being shown in Figs. 1 and 2 as being supported by a frame 2 so that the same is rotatable on a horizontal axis. The mixing drum 1 has a movable top which is designated by the numeral 3, and which is secured to the same by any preferred form of locking means; for instance as shown in Figs. 1 and 2 of the drawings. This supporting structure involved may also have mounted thereon a clutch to regulate the

speed or to stop the rotation of the drum when desired.

My invention resides primarily in the specific structure and shape of the mixing drum itself, and all the incidental structure shown with respect thereto, is merely a preferred form, but any particular form will accomplish the purpose; that is the rotation of the drum on a horizontal axis, may be used.

The mixing drum 1 comprises a pair of flat sides 5 and 6, which are parallel with the horizontal axis of the drum, and are disposed on either side of the same. These flat sides 5 and 6 diverge outwardly from their lower ends, and the said lower ends of the same are connected by an outwardly curved side 7 which is arcuate in cross section, and this arcuate side 7 with the flat sides 5 and 6 of the drum, is formed integrally so that when the same is in position as shown in Fig. 3 of the drawings, and with the cover removed therefrom, is substantially U-shaped in cross section.

To the upper edges of the flat sides 5 and 6 is secured an outwardly curved top side 8 which is arcuate in cross section, and is removably attached to the said upper edges. This cover 8 is removably secured in position by any desired form of attaching means, it being essential that the same be firmly and securely held thereto during the operation of this drum, and also that it may be easily and quickly removed therefrom when it is desired to dump the batch of concrete after the same has been mixed. The top side 8 may be provided with a handle 9 to facilitate its removal from the drum for the aforesaid purpose. This drum is provided with end plates 10 at either end, which conform to the cross sectional outline of the drum, and are secured to the edges of the same by any desired means.

In operation, the top side 8 of cover 3 of this mixing drum is removed when the drum is in position as shown in Fig. 3 of the drawing; that is the first position, and a batch of material to be mixed is poured therein, said material coming up to the level as shown in Fig. 3 of the drawing; that is a short distance below the horizontal axis of the said drum. The cover 8 is then placed thereon, and securely fastened in position and the drum is rotated. As the drum begins to move, the material which is positioned in the bottom of the same and covers

the inner surface of the curved side 7, will be carried along by gravity. When the mixer turns in the direction of the arrow, the particles begin to roll along the round-
5 ed bottom, whereby they will be moved from the same and lodged on the flat side 6 of the drum. This will be accomplished in the first quarter turn of the drum, and the material will assume the position as shown in
10 Fig. 4 of the drawings. Further rotation of the drum will cause the material to take the nature of a tilting motion, until it lodges on the curved surface of the top side 8 of the drum, as clearly shown in Fig. 5 of the
15 drawings. When in this position, the drum will have rotated one-half way around, and further rotation still in the direction of the arrow will move the material from the curved surface of the top side 8 to the flat
20 side 5 of the drum, it once more being given a rolling motion upon said movement. This position is clearly shown in Fig. 6 of the drawing, and from the said position further rotation of the drum will bring it back to
25 the original position as shown in Fig. 3. By this operation, it can be readily seen that at every revolution of the drum, the material makes four different movements. This is caused by the fact that the flat sides 5 and
30 6 of the drum diverge outwardly; hence, on the material being rolled on one of the sides, for instance, on the side 6, as shown in Fig. 4, the same will slant downwardly, and when it is rolled onto the side 5 as shown in
35 Fig. 6, the same will slant upwardly. Thus it will be obvious that the material in this drum upon rotation of the same, will be subjected to a rolling and tilting movement, and as has been hereinbefore stated, will be sub-
40 jected to four different movements upon each rotation of said drum, whereby the material will be easily and efficiently mixed without the need of any additional accessories dis-
posed inside of the drum.
45 This rotatable drum may be inserted if

desired in any type of concrete mixing system, or it may be used alone for various other kinds of mixing. On account of the novel shape of the drum, the same presents an inner surface upon which the material 50 moves without any sharp angles in which the material would be likely to clog and prevent a perfect mixing.

From the foregoing description of the construction of my improved device, the manner of applying the same to use, and the operation thereof will be readily understood, and it will be seen that I have provided a simple, inexpensive, and efficient means for carrying out the objects of the invention. 55 60

I claim:

A horizontal rotary cement mixing drum comprising a pair of flat opposed sides of equal width lying parallel with and spaced equidistantly from the axis of the drum, 65 said sides being disposed in approximately upright planes but having their upper edges spaced apart a greater distance than their lower edges, a bottom connecting said lower edges of the sides and joining the latter at 70 obtuse angles thereto, said bottom lying parallel to the aforesaid axis and being curved in transverse section on an arc described around the same, a removable top extending between the upper edges of the sides and lying parallel to the drum axis, said top being curved in transverse section on an arc de- 75 scribed around a point below said axis on a vertical line passing through the latter, and a pair of ends between which the sides, bot- 80 tom and top extend, said ends being disposed in parallel planes at right angles to the drum axis.

In testimony whereof I have hereunto set my hand in presence of two subscribing wit- 85 nesses.

HERMAN JUILFS.
